CONTAINER TRANSFER APPARATUS

Frederick W. Hankins, Philadelphia, and Fred-
erick K. Fildes, Altoona, Pa.

Application August 17, 1933, Serial No. 685,522

14 Claims. (Cl. 214—38)

Our invention relates to apparatus for transferring railway containers or like objects from one platform to another, as from railway car to railway car, from car to truck, from car to stationary platform, or vice versa, the invention being particularly useful at stations where cranes or other container handling facilities are not available.

The principal object of the invention is to provide a simple, inexpensive and efficient means for handling containers which are carried on railway cars or other vehicles in raised position with respect to the vehicle platform, or which are adapted to be raised a sufficient distance to allow the insertion of a carriage in the space between the vehicle platform and the bottom of a container.

Another object of the invention is to provide movable to a position alongside the vehicle to be served, and which includes in a self-contained unit of relatively small size means in the nature of a trackway for bridging the space between the transfer unit and vehicle, and a container supporting carriage adapted for movement along said bridging trackway.

Another object of this invention is to provide in apparatus of the character described means for adjusting the level of the transfer unit with respect to the level of the vehicle served thereby so that the bridging trackway may be caused to be inclined downwardly in the direction in which a container is to be moved.

Still another object of this invention is to provide in apparatus of the character described a revolvable turntable which is adapted to support a container and to turn the same to face in any desired direction, thus rendering the use of the transfer apparatus extremely flexible.

Still other more specific objects and advantages characterizing this invention will become apparent from the detailed description of one embodiment or example thereof which follows hereinafter, having reference to the accompanying drawings. Of the drawings:

Fig. I represents a plan view of transfer apparatus of my invention, showing a typical arrangement of station platform, railway track and truck runway to which the invention is well adapted.

Fig. II represents an enlarged side elevation of the transfer apparatus operating to shift containers between a railway car and a trailer.

Fig. III represents an enlarged side elevation of the transfer apparatus operating to shift con-

tainers from the transfer apparatus to a trailer.

Fig. IV represents an enlarged plan view of the transfer apparatus with its parts extended over a railway car.

Fig. V represents an end elevation of the transfer apparatus.

Fig. VI represents a plan view of the transfer apparatus with parts broken away to better disclose important features.

Fig. VII represents a cross section, taken as indicated by the lines VII—VII of Fig. I.

Fig. VIII represents a detailed side view of the skid of the transfer apparatus in its extended position showing a portion of the turntable in section, indicated by the lines VIII—VIII in Fig. IV.

Fig. IX represents a detailed side view of the skid of the transfer apparatus previous to complete extension.

Fig. X represents a plan view of one of the corners of the transfer apparatus; and

Fig. XI represents a cross section taken as indicated by the lines XI—XI of Fig. V.

With particular reference to Fig. I, there is represented in the drawings a typical transfer station arrangement to which this invention may be applied to advantage. The transfer apparatus is comprehensively designated at 1, and moves along a track formed of spaced parallel rails 2. At one side of the rails 2 and parallel therewith, there is shown a section of railway track 3 with cars 4 thereon carrying shipping containers 5. At the other side of the rails 2 and parallel therewith, there is an elevated platform 6 and a truck runway 7 in which space we have shown conventionally a trailer vehicle 8. An additional railway track is represented at 3a having a dead end adjacent to the truck runway 7. On the railway track 3a there is shown a car 4a with containers 5a thereon. It will, of course, be understood that the above transfer station arrangement is simply representative of a typical practice of our invention, and that many other arrangements are embraced within the invention.

With reference to Figs. IV—XI, wherein the transfer apparatus is shown in detail, it will be seen that this apparatus comprises generally a main frame 9, rectangular in shape and mounted on flanged wheels 10 which engage the rails 2, and an adjustable platform 11 mounted on the frame 9 by means of hydraulic jacks 12. On the platform 11, which in the illustrated example is rectangular and made up of channel beams, there is mounted a turntable 13 having spaced parallel grooves 14 thereon which normally house a skid 15. The

skid 15 comprises generally a pair of parallel rails 16 guided for movement along the grooves 14 of the turntable 13 and adapted to be extended outwardly beyond the turntable to a position 5 overlying either the railway track 3, the railway track 3a, the station platform 6 or the truck runway 7, depending upon the location of the transfer unit 1 and the position of its turntable 13. A container supporting carriage 17 10 with flanged rollers 18 is mounted for movement on the skid rails 16 as well as on the raised surfaces 19 adjacent to the grooves 14 of the turntable 13 which form therewith a trackway for the rollers 18.

15 The transfer unit 1 may, of course, be constructed in many different forms. Essentially its main frame 9 must be rugged and sufficiently strong to support the superimposed weight of a loaded container, and accordingly, channel beams 20 of conventional form are preferably used for its construction. At the four corners of the frame 9 are mounted the hydraulic jacks 12, each of which includes a rod 21 which joins the elevated platform 11 with a pivotal connection 70 to allow 25 tilting of the platform to a slope of about three degrees in a direction transverse to the rails 2. This pivotal connection 70, clearly shown in Fig. XII, is a mechanical expedient well known in the art, and consists of a rounded head 71 and spud 72 30 formed at the top of the rod 21, and a socket 73 formed in the corners of the platform 11. The radius of the curve of the head 71 is smaller than the radius of the curve of the socket 73; and this, with the clearance for the spud 72 as indicated, allows a tilting of the platform 11 three 35 degrees and ten minutes. Each pair of hydraulic jacks 12 at each side of the frame 9 is connected to a pump 22 disposed at that side of the frame, see Figs. II and IV. In an obvious manner by 40 operating one pump 22 or the other the platform 11 may be inclined in the desired direction transversely of the rails 2.

A circular beveled track 23 with a geared periphery 24 is mounted at the top of the platform 45 11 and has at its center a bearing 25 which receives a vertical shaft 26 of the turntable 13 about which the turntable rotates, see Fig. VI. The turntable 13 may be made of welded plates, or may be cast in one piece, and is provided at the under 50 side thereof with beveled rollers 27 disposed radially and adapted to roll freely on the raceway afforded by the track 23. Rotation of the turntable 13 is accomplished by means of a spur gear 28 mounted on the turntable and meshing with the 55 gear teeth 24 on the periphery of the circular track 23. The spur gear 28 is, in turn, driven through bevel gears 30 and a shaft 31 which terminates in a nut-shaped end 32 to which a similarly shaped socket of a hand crank may be 60 applied, see Figs. VI and XI.

The parallel grooves 14 at the top surface of the turntable 13 extend throughout the length of the table and are most clearly illustrated in Figs. IV, VII, VIII and IX. At the bottom of 65 each groove 14 there is a flat surface 33 upon which rollers 34 attached to the skid rails 16 are adapted to travel. The skid rails 16 are of channel shaped formation and when housed within the grooves 14 are disposed with their top 70 surfaces beneath the level of the raised surfaces 19 upon which the carriage rollers 18 bear, Figs. VII-IX. The centrally flanged rollers 18 of the carriage 17 ride out on the skid rails 16 when in their extended position, and when the skid rails 75 16 are on the turntable, the rollers 18 bear en-

tirely upon the surfaces 19 adjacent to the grooves 14, and are clear of the skid rails 16. Accordingly when the carriage 17 is on the turntable 13, the skid rails 16 may be freely moved, for in that event they do not carry the weight of 5 the carriage.

The inner ends of the skid rails 16 are rounded off as indicated at 37 and likewise the rolling surfaces 19 of the turntable 13 are smoothly rounded as indicated at 38 in order that the carriage 17 will roll smoothly from one surface to the other when the skid rails 16 are extended and sloped either away from or toward the turntable. Moreover, in order to bring the inner ends of the skid rails 16 to a level with the rolling surfaces 15 19 when the skid is extended, so that the carriage 17 can roll smoothly from one surface to the other, the bottom surfaces 33 of the grooves 14 are raised at the outer ends of the grooves by the insertion of plates 39 with inclined surfaces 40 20 leading thereto. The plates 39 are so disposed as to preserve the unhampered or free movement of the skid rails 16 when the carriage 17 is on the turntable 13, as clearly shown in Figs. VII 25 and IX.

Because of the restrictions on the space available between the bottom of a raised container and the carrier platform, the carriage 17 is constructed with its rollers 18 mounted well up within the beams 42 of which the frame of the carriage is constructed, and the beams 42 are reduced to a minimum height consistent with the strength required to support a loaded container. To restrain the carriage 17 from running off the skid 15, the cross piece 43 which joins the outer 35 ends of the skid rails 16 is raised to provide a stop, Fig. VIII. Moreover, on the turntable 13 there are raised abutments 44 which serve as stops 40 limiting the movement of the carriage in the opposite direction, Figs. IV and V.

The skid 15 is extended and retrieved by a hand operated windlass 45 attached to the turntable 13 at a point opposite the side over which the skid 15 is extended. Lines 47 for extending the skid 15 wind around the windlass 45 and lead across 45 the turntable 13 through sheaves 48 and are attached to the inner ends of the skid rails 16. A skid retrieving line 49 is fastened to the outer end of the skid 15 and winds around the windlass 45 in a direction opposite to the skid extending 50 lines 47. By this arrangement, the turning of the windlass 45 in one direction winds up the retrieving line 49 and unwinds the extending lines 47, thereby retrieving the skid 15. Turning the windlass 45 in the opposite direction similarly 55 brings about an extension of the skid 15. The windlass 45 is hand operated by a hand crank applied to a square ended shaft 50.

Adjacent to the windlass 45 there is an additional hand operated windlass 51 for propelling 60 the carriage 17 which is operated in a like manner by applying a crank to a shaft 52. Both windlasses 45 and 51 are preferably driven through worm gears disposed within the casings 54 and are therefore locked against movement 65 except when power is applied to their operating shafts. A carriage line 55 for propelling the carriage 17 winds around the carriage windlass 51 several times to frictionally engage the drum, with one end fastened to the inner end of the carriage 17 and the other end leading out and around a sheave 56 mounted on the cross piece 43 and attached to the outer end of the carriage 17. The windlass 51 operates in the usual manner, winding in one end of the line 55 and unwinding 70 75 75

and paying out the other end as the windlass 51 is turned. By this arrangement, the carriage 17 may be moved back and forth by turning the shaft 52 in one direction or the other.

5 At the outer end of the skid 15 and preferably near the cross piece 43 there is provided at the underside of each skid rail 16, a hydraulic jack 58 for raising the outer end of the skid. The hydraulic jacks 58 are adapted to be seated on the platform of a container vehicle, as shown in Figs. II, IV and VIII and are controlled by a hydraulic pump 59 mounted on the turntable 13 and connected to the hydraulic jacks 58 by flexible tubing 60.

15 A typical example of the operation of the container transfer apparatus herein described is as follows: In the event that it is desired to transfer a container 5 from a car 4 standing on the track 3 to a trailer 8 disposed at the other side of the rails 2, the transfer unit 1 is first moved along the rails 2 to a position abreast of the particular container 5 which it is desired to shift. The operator then elevates the turntable 13 of the transfer unit 1 to a level slightly above the floor 62 of the car 4 by alternately operating the two hydraulic pumps 22 which control movement of the hydraulic jacks 12. By applying the crank handle to the nut shaped end 32 of the shaft 31, the turntable 13 is rotated until it assumes a position transverse to the rails 2. Then by applying the same crank handle to the shaft 50 of the windlass 45, the windlass 45 is operated to cause the skid 15 to be extended outwardly beyond the confines of the turntable into the space between the bottom of the container 5 and the platform 62 of the container vehicle 4. Inasmuch as the windlass 45 is driven through worm gearing, the skid 15 will be held in its extended position. The operator then applies the same crank handle to the operating shaft 52 of the windlass 51, and the windlass 51 is operated to cause the carriage 17 to be run out onto the skid rails 16 to a position underneath the container to be moved. It will be noted that the carriage 17 will be locked in its new position because operated through worm gearing.

When the skid 15 and its carriage 17 are thus positioned between the car floor 62 and the bottom of a container thereon, the operator proceeds to operate the hydraulic pump 59 to raise the elevating jacks 58, and thereby elevate the outer end of the skid 15 until the load of the container is transferred from its seat on the car platform 62 to the carriage 17, Fig. II. The skid rails 16 will then be sloped downward from the car 4 toward the turntable 13, and this obviously reduces the amount of energy necessary to move the carriage 17 with its load onto the turntable 13, in the direction of the arrow. If desirable the turntable 13 may also be sloped in a direction and at an angle corresponding to the slope of the skid rails 16 by operating the hydraulic pumps 22. When all is in readiness to transfer the container onto the turntable 13, the carriage 17 is propelled through operation of the windlass 51. Incident to its movement the flange rollers 18 of the carriage 17 will roll freely off the inner ends of the skid rails 16 onto the rolling surfaces 19 of the turntable 13.

70 When the container 5 has been thus positioned on the turntable 13, the skid 15 is lowered by depressing the hydraulic jack 58 to the point where the rollers 18 at the outer end of the skid again rest upon the car platform 62, Fig. VIII. The skid 15 is then retrieved or returned to its

normal housed position within the turntable by operation of the windlass 45.

The transfer unit 1 is then moved along the rails 2 to a position abreast the trailer vehicle 8. When the transfer unit is so positioned the operator applies his crank handle to the shaft 31 and rotates the turntable 13 through an arc of one hundred eighty degrees. The transfer table 1 is then elevated to a level above the floor of the trailer vehicle 8, the skid 15 is extended outwardly onto the floor of the trailer vehicle, and raised by the jack 58 and the carriage 17 with the container 5 thereon is transferred to the floor of the trailer vehicle, Fig. III. It will be understood that the container is supported in a raised position on the floor of the trailer vehicle so that by operation of the hydraulic jack 58 at the end of the skid 15 the load can be transferred from the carriage 17 to the container supports on the trailer vehicle.

If it is desired to transfer a container from the railway car 4 to the station platform 6, this movement can be accomplished in the manner similar to the car to truck transfer. Furthermore, containers 5a from the car 4a on the track 3a may obviously be shifted by the apparatus of this invention to the trailer vehicle 8, to the car 4, or to the platform 6 as desired.

It will be apparent that the container transfer apparatus of our invention is extremely flexible in its operation and may be employed in many different ways from those particularly described herein to shift containers laterally from one elevated platform to another. It will also be observed that the skid 15 and its carriage 17 are normally maintained within the confines of the main frame 9 of the transfer unit so that the unit may be safely operated in a position alongside a railway track without danger of any of its parts striking vehicles moving on the railway track.

While our invention has been described in some detail with reference to a specific embodiment thereof, various changes in the form of the apparatus are contemplated, and such changes should not be deemed to constitute a departure from the spirit of the invention as hereinafter claimed.

Having thus described our invention, we claim:

1. Transfer apparatus for railway containers comprising a movable frame, a revolvable turntable mounted on said frame and having a trackway formed thereon, a skid movable on said turntable and adapted to be extended outwardly thereof to provide rails in continuation of said trackway, and a container supporting carriage mounted for movement on said trackway and skid.

2. Transfer apparatus for railway containers comprising a movable frame, a revolvable turntable mounted on said frame and having a trackway formed thereon, a skid movable on said turntable and adapted to be extended outwardly thereof to provide rails in continuation of said trackway, elevating means attached to the outer end of said skid and adapted for engagement with a container carrying platform, and a container supporting carriage mounted for movement on said trackway and skid.

3. Transfer apparatus for railway containers comprising a movable frame, a revolvable and vertically movable turntable mounted on said frame and having a trackway formed thereon, means for elevating and depressing the turntable, an extensible skid mounted on said turntable and adapted when extended to provide rails in continuation of said trackway, jacking means attached to the outer end of said skid and adapted for engagement with a container carrying plat-

form, and a carriage mounted for movement on said trackway and skid.

4. Transfer apparatus for railway containers comprising a wheeled frame, vertically adjustable supports mounted on the frame, a platform mounted on the adjustable supports, a revolvable turntable mounted on the platform and having a trackway formed thereon, an extensible skid mounted on said turntable and adapted when extended to provide rails in continuation of said trackway, jacking means attached to the outer end of said skid, and a carriage mounted for movement on said trackway and skid.

5. Transfer apparatus for railway containers comprising a wheeled frame, a revolvable turntable mounted on said frame and having a trackway formed thereon, an extensible skid mounted on said turntable and adapted when extended to provide rails in continuation of said trackway, jacking means attached to the outer end of said skid for adjustably supporting the same on a container carrying platform, means mounted on said frame and having a flexible connection to said jacking means for controlling the raising and depressing of said skid, and a carriage mounted for movement on said trackway and skid.

6. Transfer apparatus for railway containers comprising a wheeled frame, a revolvable turntable mounted on said frame and having a trackway formed thereon, independent means for elevating each side of the turntable, an extensible skid mounted on said turntable and adapted when extended to provide rails in continuation of said trackway, means on said turntable for moving said skid to extended and retracted positions, and a carriage movable on said trackway and skid.

7. Transfer apparatus for railway containers comprising a wheeled frame, a revolvable turntable mounted on said frame and having a trackway formed thereon, an extensible skid in the form of rails normally housed within the turntable and beneath the running surfaces of the trackway and adapted to be projected outwardly from said turntable to form a continuation of said running surfaces, and a carriage movable on said trackway and skid rails.

8. Transfer apparatus for railway containers comprising, in combination with a track for container vehicles and a second track parallel therewith, a wheeled frame movable on said second track, a revolvable turntable mounted on said frame and having a trackway formed thereon, a skid movable on said turntable and adapted to be extended outwardly thereof to a position overlying said first track and when thus extended providing rails in continuation of said trackway, and a container supporting carriage mounted for movement on said trackway and skids.

60 9. Transfer apparatus for railway containers comprising in combination with a track for container vehicles and a second track parallel therewith, a wheeled frame movable on said second track, a revolvable turntable mounted on said frame and having a trackway formed thereon, a skid movable on said turntable and adapted to be extended outwardly thereof and when thus extended providing rails in continuation of said trackway, elevating means attached to the outer end of said skid and adapted for engagement with the platform of a container vehicle on said first track, and a container supporting carriage mounted for movement on said trackway and skids.

10. Transfer apparatus for railway containers comprising in combination with a vehicle having a platform and a container spaced above said platform, a wheeled frame adapted to be positioned alongside said vehicle, a skid normally housed within said frame and extensible outwardly thereof, a carriage movable on said skid, said skid and carriage being adapted to enter into the space between the platform of the container vehicle and the bottom of a container thereon, and jacking means adapted to be interposed between said platform and the outer end of said skid.

11. Transfer apparatus for railway containers comprising in combination with a vehicle having a platform and a container spaced above said platform, a wheeled frame adapted to be positioned alongside said vehicle, a table mounted on said frame, means for elevating and depressing said table to levels above and beneath the platform of the container vehicle, a skid normally housed within the confines of said table and extensible outwardly thereof, a carriage movable on said skid, said skid and carriage being adapted to enter into the space between the platform of the container vehicle and the bottom of a container thereon, and jacking means adapted to be interposed between said platform and the outer end of said skid.

12. Transfer apparatus for railway containers comprising in combination with a vehicle having a platform and a container spaced above said platform, a wheeled frame adapted to be positioned alongside said vehicle, a turntable mounted on said frame and having a trackway formed thereon, a skid normally housed within said turntable and extensible outwardly thereof, a carriage movable on said skid, said skid and carriage being adapted to enter into the space between the platform of the container vehicle and the bottom of a container thereon, means on said wheeled frame for extending and retrieving said skid, and additional means on said wheeled frame for moving said carriage on said skid.

13. Transfer apparatus for railway containers comprising a movable frame, a revolvable turntable mounted on said frame and having a trackway formed thereon, a skid movable on said turntable and adapted to be extended outwardly thereof to provide rails in continuation of said trackway, means on the turntable for extending and retrieving the skid; and a container supporting carriage mounted for movement on said trackway and skid.

14. Transfer apparatus for railway containers comprising in combination with a vehicle having a platform and a container spaced above said platform, a wheeled frame adapted to be positioned alongside said vehicle, a turntable mounted on said frame and having a trackway formed thereon, a skid normally housed within said table and extensible outwardly thereof, a carriage movable on said skid, said skid and carriage being adapted to enter into the space between the platform of the container vehicle and the bottom of a container thereon, means on said turntable for extending and retrieving said skid, and means on said wheeled frame for moving said carriage on said skid.

FREDERICK W. HANKINS. 70
FREDERICK K. FILDES.
